FOR ANALYZING GASES**

Milton E. Krogh, deceased, late of Dallas, Tex., by Mary Frances Krogh, executrix, Dallas, Tex., assignor to The Atlantic Refining Company, Philadelphia, Pa., a corporation of Pennsylvania

Application January 28, 1953, Serial No. 333,694

5 Claims. (Cl. 23—232)

This invention relates to apparatus for detecting the presence of combustible gases in a stream of gases of unknown composition, and more particularly to apparatus for determining whether combustible gases separated from the returning mud stream during the drilling of a well comprise predominantly methane to the substantial exclusion of higher hydrocarbon gases, or comprise higher hydrocarbon gases with or without the presence of methane.

In the drilling of oil wells by the rotary drilling method wherein a drilling fluid, or mud, is used to lubricate the bit and carry cuttings out of the well, it has recently become fairly common practice to examine the returning mud stream for the presence therein of hydrocarbons, whereby to determine whether the drill bit has penetrated a hydrocarbon-bearing formation. According to the one well known method, a gas trap is connected to the returning mud line to continuously separate and withdraw a portion of the gases which may be present in the returning mud stream. Gases thus withdrawn from the mud stream are mixed with air and then passed to a combustible-gas detector which produces electrical signals in accordance with the concentration of gaseous hydrocarbons present in such gases. Usually, and preferably, the gas detector is connected with a recording apparatus on which the electrical signals from the gas detector are recorded either in accordance with well depth or as a function of time.

Presently available apparatus of the above described type is capable of indicating the presence of hydrocarbons generally in the returning mud stream from a drilling well, and thus indicating the existence of hydrocarbon-bearing formations. However, in order to obtain more detailed information as to strata penetrated by the boreholes, it is desirable to know whether the particular formations contain gas or oil. In this connection, it has been found that when the gases detected in the returning mud stream from a drilling well comprise predominantly methane, the formation penetrated is probably a gas bearing formation; whereas if the detected gases comprise the higher normally gaseous hydrocarbons the penetrated formation is probably an oil-bearing formation.

There are, of course, presently available combustible-gas detectors capable of adjustment for detecting either the presence of the higher gaseous hydrocarbons irrespective of the presence of methane, or the presence of all normally gaseous hydrocarbons including methane. However, there has not heretofore been provided any completely integrated and automatically operated apparatus which is capable of taking a sample of gas from the returning mud stream from a drilling well and automatically giving an indication as to whether said gas sample contains predominantly methane or whether it also contains substantial components of the higher hydrocarbons.

Accordingly, it is one object of the present invention to provide an apparatus for detecting gaseous hydrocarbons in the returning mud stream from an oil well and auto-

2
matically giving an indication as to whether the detected gaseous hydrocarbons comprise hydrocarbons higher than methane, or predominantly methane to the substantial exclusion of higher hydrocarbons.

5 It is another object of this invention to provide a combustible-gas detecting and recording apparatus having two detector elements, one of which is adaptable to indicate the presence of all normally gaseous hydrocarbons including methane, and the other of which is adapted to indicate the presence of only higher gaseous hydrocarbons irrespective of the presence of methane.

10 It is a further object of this invention to provide apparatus for examining the gases separated from the returning mud-stream from a drilling well comprising a first detector for detecting the presence of higher gaseous hydrocarbons irrespective of the presence of methane, a second detector capable of detecting the presence of all normally gaseous hydrocarbons including methane, a recorder adaptable to receive and record signals from either of said detectors, and automatic switch means for periodically and alternately connecting each of said detectors to said recorder.

15 Other objects and advantages will become apparent from the following detailed description taken in connection with the appended drawing.

20 In the drawing Figure 1 is a schematic diagram of a preferred embodiment of the apparatus of the present invention.

25 Figure 2 is a schematic representation of the electrical circuit of a typical filament-type combustible-gas detector which forms a component part of the apparatus of this invention.

30 Figure 3 is a representation of a section of a recording chart which might be produced by the apparatus of Figure 1.

35 Briefly, the apparatus of the present invention comprises two combustible-gas detectors through which a sample of gas of unknown composition is adapted to pass, a recorder for recording signals emitted by each 40 of the detectors in accordance with the concentration of combustible gases detected, and automatic switch means for alternatively and periodically connecting each of the detectors to the recorder.

45 In the drawing numeral 1 denotes the flow line through which drilling fluid returns from the drill hole to the mud pit. Attached at any convenient location 2 along line 1, as by welding, is gas trap 3 which is in communication with the interior of line 1, and in which gas 50 liberated from the drilling fluid will collect in the well known manner. Gas trap 3 may be of any conventional design or type. The gas collected in gas trap 3 is mixed with air which enters gas trap 3 through nipple 4, and is then carried by conduit 5 through a first combustible-gas detector 6, which by way of illustration, is preferably 55 a detector of the well known hot-filament type which produces an electrical signal proportional to the amount of gaseous hydrocarbons higher than methane which are present in the gas stream; and thence through a second combustible-gas detector 7 which is also preferably of the hot-filament type but which produces an electrical signal 60 proportional to the amount of total gaseous hydrocarbons, including methane, present in the gas stream. After passage through the gas detectors, the gas is exhausted to the atmosphere through vacuum pump 8. The electrical output signal from detector 6 is supplied through wires 9 to one set of fixed terminals 10 of switch 11, and the electrical output signal of detector 7 is supplied through wires 12 to another set of fixed terminals 13 of switch 11. A set of movable terminals 14, to which are connected wires 15, are adapted to be moved selectively to contact with fixed contacts 10 and 13 whereby to selectively supply the electrical signals from wires 9 and 12,

respectively, to a conventional recording potentiometer 16 of the type, well known to those skilled in the art of such instruments, which has a stylus 17 movable across the face of chart 18 in accordance with variations in the electrical signals applied through wires 15. Chart 18 may be driven in accordance either with time or with the rate of progress of the drill bit in the well from which drilling fluid passing through line 1 is flowing.

Hot-filament combustible-gas detectors 6 and 7 per se are not within the scope of the present invention since detectors of this type, such, for instance, as illustrated in the patent to Bliss et al. No. 2,514,690, are well known to those skilled in the art. Such detectors, as illustrated in Figure 2, comprise a filament 19 which forms one arm of a Wheatstone bridge circuit 20 and which is adapted to be contacted by the gas to be analyzed. The other arms of the bridge comprise a compensator element 21, and resistances 22 and 23, respectively. Voltage supplied by battery 24, or other suitable source, across points 25 and 26 of bridge 20 serves to maintain filament 19 at an elevated temperature sufficient to cause ignition of the desired combustible components of the gases which pass in contact therewith. Output leads 27 and 28, which, it will be understood, correspond to leads 9 of detector 6 or leads 12 of detector 7, are connected across point 29 and potentiometer 30 to supply the output of the bridge circuit to a suitable measuring and recording device. It will be understood that potentiometer 30 is so adjusted that there will be no voltage difference between leads 27 and 28 when gases to which filament 19 is exposed contain no combustible components ignitable at the temperature of the filament. It will be appreciated by those familiar with such detectors that the rise in temperature of filament 19, due to the ignition of combustible components which later appear in the gases contacting the filament, acts to change the resistance of the filament and thus causes an unbalance of bridge 20 and a measurable difference in potential between the output leads 27 and 28.

As is well known to those skilled in the art, methane, being more stable than the higher normally gaseous hydrocarbons requires a higher temperature to induce ignition. Therefore, it will be appreciated that the filament of a typical hot-filament detector may be operated at a temperature which is sufficiently high to induce ignition of the higher hydrocarbons which come in contact therewith and yet be insensitive to the presence of methane. On the other hand, if the filament of the detector is operated at a temperature sufficient to induce ignition of methane which passes in contact therewith, it will also induce the ignition of higher gaseous hydrocarbons which also contact it. Thus, by passing a sample of gas first through a detector having the filament at a temperature only sufficient to cause ignition of the higher hydrocarbons which contact the filament, and then through a detector having its filament at a temperature sufficiently high to cause ignition of methane and the higher hydrocarbons which come in contact therewith, and comparing the electrical outputs of the two detectors, it is possible to determine whether the sample of gas contains predominantly methane, or methane accompanied by substantial amounts of the higher hydrocarbons, and the proportions of these gases.

Those skilled in the art will appreciate that the operating temperature of the filament of the detector which is adapted to detect only the higher hydrocarbons may be established empirically by adjusting the temperature in the presence of gas of known composition to a temperature such that it will cause ignition of the higher hydrocarbons, but will not cause the ignition of methane alone. Likewise, the temperature of the filament of the detector for detecting all hydrocarbons, including methane, may be established empirically by adjusting the temperature thereof sufficiently high to induce the ignition of methane in a sample of known composition. Satisfactory results

have been obtained by employing operating temperatures of approximately 450° C. and approximately 550° C., respectively, for the filaments of the two detectors.

In connection with the specific apparatus described herein, therefore, it will be appreciated that the filament of detector 6 is adjusted to a temperature sufficient to cause ignition of normally gaseous hydrocarbons higher than methane which pass in contact with the filament, but not methane; whereas the filament of detector 7 is adjusted to a temperature sufficient to induce ignition of all normally gaseous hydrocarbons, including methane, which pass in contact therewith.

Referring now to switch 11, it is to be understood that this switch may be of any suitable type for alternatively connecting either wires 9 or wires 12 with wires 15, which are in turn connected to recorder 16. By way of illustration, switch 11 has been shown in Figure 1 as comprising fixed terminals 10 to which wires 9 are connected, fixed terminals 13 to which wires 12 are connected, and movable terminals 14 which are secured to movable member 31. In the particular embodiment shown, movable member 31 is adapted to be operated by rod 32 which forms the armature of solenoid 33, the coil of which is adapted to be supplied with current periodically from timer controlled source 34 through leads 35. Movable member 31 is adapted to be held in its extreme right-hand position by spring 36, and to be moved to its extreme left-hand position upon energization of the coil of solenoid 33 which serves to move rod 32 to the left, as will be appreciated by those familiar with the operation of solenoids. The current supplied to leads 35 may be obtained from any source, not shown, such as a 115-volt 60-cycle supply line, or from batteries; and the timing mechanism of timer controlled source 34 may be either mechanical or electrical, these details not being a part of this invention.

In operation, with mud flowing through line 1, the gas and air mixture entering gas trap 3 will be drawn through conduit 5 and through detectors 6 and 7 under suction provided by suction pump 8. Timer-controlled source 34, by alternately supplying and discontinuing power to solenoid 33, causes the movable member 31 of switch 11 to reciprocate between its right-hand and left-hand positions whereby to alternately connect movable terminals 14 with fixed terminals 13 and fixed terminals 10. Timing mechanism 34 may be adjusted to cause movable member 31 to operate on any desired cycle; however, an arrangement whereby movable member 31 reverses its position every 30 seconds has been found to be satisfactory.

With such an arrangement it will be appreciated that during one 30-second interval, the stylus 17 of recorder 16 will occupy on chart 18 a position indicative of the concentration of total gaseous hydrocarbons, as indicated by the signal from detector 7, transmitted through wires 12, switch 11, and wires 15, and that during the next 30-second interval, the stylus 17 will occupy a position on chart 18 indicative of the concentration of gaseous hydrocarbons higher than methane, as indicated by the signal from detector 6, transmitted through wires 9, switch 11, and wires 15. Thus if stylus 17 indicates a positive reading when recorder 16 is connected with detector 7, and a zero reading when recorder 16 is connected with detector 6, this fact is indicative of the presence of methane, without higher gaseous hydrocarbons, in the gases flowing through conduit 5 and the detectors. On the other hand, it will be understood that when stylus 17 indicates a positive reading both when recorder 16 is connected with detector 6 and when it is connected with detector 7, that fact indicates that gaseous hydrocarbons higher than methane are present. Also, it will be appreciated that since detector 7 indicates concentration of total gaseous hydrocarbons and detector 6 indicates only concentration of gaseous hydrocarbons higher than methane, a comparison of the respective positions of stylus 17 when the

recorder is connected with detectors 6 and 7 respectively, provides an indication of the relative concentration of methane and higher gaseous hydrocarbons.

It will be understood that in the normal operation of filament-type combustible-gas detectors, only those combustible components of the gas stream which come into direct contact with the filament are ignited. Since only an infinitesimally small proportion of the total gas flowing in the stream actually contacts the filament, it will be appreciated that the composition of the total gas mass comprising the stream is not substantially affected by the ignition caused by the filament. Thus, in the specific apparatus disclosed in Figure 1, the signal generated by detector 7 will, for all practical purposes, be proportional to the amount of all normally gaseous hydrocarbons originally present in the stream of gases as it left gas trap 3, even though there may be present therein higher gaseous hydrocarbons ignitable at the temperature of the filament of detector 6.

In Figure 3 there is shown a section of a chart of the type which might be produced by the recorder of an apparatus of the type described above. On this chart 18 the segments 37 represent the position of the stylus 17 when recorder 16 was connected with the output of detector 7 (that is, the detector having its filament at a temperature sufficient to ignite methane) and segments 38 represent the position of the stylus when recorder 16 was connected to the output of detector 6 (that is, the recorder having its filament at a temperature sufficient to ignite only hydrocarbons higher than methane). From an examination of the section of chart shown in Figure 3, it will be seen that the combustible gases detected as indicated between points 39 and 40 on the chart comprised predominantly methane, whereas the gases indicated between points 41 and 42 contained substantial amounts of higher hydrocarbons as well.

While there is shown and described only one embodiment of this invention, it will be appreciated by those skilled in the art that many changes might be made thereto without departing from the scope of this invention; for instance, the relative positions of detectors 6 and 7 may be reversed, so that the gas flowing through conduit 5 first comes in contact with the detector capable of detecting all gaseous hydrocarbons, including methane, and thereafter comes in contact with the detector which is capable of detecting only the higher gaseous hydrocarbons. Therefore, it is to be understood that this invention is not to be limited by the above description but is to be limited only in accordance with the appended claims.

What is claimed is:

1. An apparatus for detecting and recording the presence of hydrocarbons in a stream of gas of unknown composition and for distinguishing between methane and normally gaseous hydrocarbons higher than methane, the combination of a first filament-type combustible-gas detector having a filament, means for maintaining said filament of said first detector at a temperature sufficiently high to cause ignition of normally gaseous hydrocarbons including methane, whereby said detector will generate a signal proportional to the amount of such gaseous hydrocarbons in said stream, a second filament-type combustible-gas detector having a filament and being of the same character as said first detector, means for maintaining said filament of said second detector at a temperature only sufficiently high to cause ignition of higher normally gaseous hydrocarbons to the exclusion of methane, whereby said second detector will generate a signal proportional to the amount of higher normally gaseous hydrocarbons in said stream, means for continuously passing said stream of gas in contact with the filament of said first detector and then the filament of said second detector, recording means having one stylus for recording the signals from either of said detectors, and automatic switch means for selectively and alternately connecting said detectors to said recording means.

2. An apparatus for detecting and recording the presence of hydrocarbons in a stream of gas of unknown composition and for distinguishing between methane and normally gaseous hydrocarbons higher than methane, the combination of a first filament-type combustible-gas detector having a filament, means for maintaining said filament of said first detector at a temperature sufficiently high to cause ignition of normally gaseous hydrocarbons including methane, whereby said detector will generate a signal proportional to the amount of such gaseous hydrocarbons in said stream, a second filament-type combustible-gas detector having a filament and being of the same character as said first detector, means for maintaining said filament of said second detector at a temperature only sufficiently high to cause ignition of normally gaseous hydrocarbons to the exclusion of methane, whereby said second detector will generate a signal proportional to the amount of higher normally gaseous hydrocarbons in said stream, means for continuously passing said stream of gas in contact with the filament of said first detector and then the filament of said second detector, recording means having one stylus for recording the signals from either of said detectors, switch means operable to selectively and alternately connect either of said detectors to said recording means, and automatic timer controlled operating means for periodically operating said switch means.

3. An apparatus for detecting and recording the presence of hydrocarbons in a stream of gas of unknown composition and for distinguishing between methane and normally gaseous hydrocarbons higher than methane, the combination of a first filament-type combustible-gas detector having a filament, means for maintaining said filament of said first detector at a temperature sufficiently high to cause ignition of normally gaseous hydrocarbons including methane, whereby said detector will generate a signal proportional to the amount of such gaseous hydrocarbons in said stream, a second filament-type combustible-gas detector having a filament and being of the same character as said first detector, means for maintaining said filament of said second detector at a temperature only sufficiently high to cause ignition of higher normally gaseous hydrocarbons to the exclusion of methane, whereby said second detector will generate a signal proportional to the amount of higher normally gaseous hydrocarbons in said stream, means for continuously passing said stream of gas in contact with the filament of said first detector and then the filament of said second detector, recording means having one stylus for alternately recording the signals from either of said detectors, switch means normally connecting one of said detectors to said recording means, and automatic timer controlled switch-operating means for periodically disconnecting said one detector from said recording means and connecting the other detector therewith.

4. In apparatus for detecting gas changes in formations encountered during drilling of a well bore by a bit while a fluid is circulated into and out of the well bore, including means for treating a series of possible gas containing specimens returned from apparently successive increments of depth of said well bore to cause gas to evolve therefrom, and means for testing the gas evolving during treatment of each said specimen for hydrocarbon gases, including a catalytic filament contacted by said gas and an electrical circuit for supplying current to said filament and means for indicating an effect produced at said filament by such catalytic combustion, the improvement comprising separate catalytic filaments; means for causing gas evolving during treatment of each said specimen to contact said filaments; and a separate similar electrical circuit for each catalytic filament, each said circuit including a source of electricity for supplying an electric current to said catalytic filament, means for adjusting the voltage of such current so as to apply a different voltage to said catalytic filaments independently and simultaneously, and

means for indicating an effect produced at each said filament by such catalytic combustion, so as to obtain an indication of the difference in ratio between the effect produced at said filaments by such different voltages for a series of such specimens returned from successive increments of depth of said well bore.

5. A method of detecting gas changes in formations encountered during drilling of a well bore by a bit while a fluid is circulated into and out of the well bore, which comprises subjecting a series of possible gas containing specimens returned from apparently successive increments of depth of said well bore to treatment to evolve gas contained therein; contacting at least a portion of the gas evolved from each said specimen with two separate catalytic filaments and in the presence of a combustion supporting gas; passing an electric current through said filaments independently and at different voltages, one said voltage being higher than the other and having a value tending to cause catalytic combustion of combustible gas components, including methane, which contact said filament, and the other said voltage being lower and having

5 a value tending to cause catalytic combustion of combustible gas components, except methane, which contact said other filament; and independently measuring, for each said specimen, an effect produced at each said separate filament by catalytic combustion and thereby determine for said successive increments of depth differences in the ratio between the measurements for said higher and lower voltage values.
